METHOD AND APPARATUS FOR THE MANUFACTURE OF VARNISH

Filed June 23, 1924

UNITED STATES PATENT OFFICE.

ELMER E. WARE, OF DETROIT, MICHIGAN, ASSIGNOR TO ACME WHITE LEAD AND COLOR WORKS, OF DETROIT, MICHIGAN, A CORPORATION OF MICHIGAN.

METHOD AND APPARATUS FOR THE MANUFACTURE OF VARNISH.

Application filed June 23, 1924. Serial No. 721,902.

The invention relates to the manufacture of varnish and has for its primary object the obtaining of a continuous process for manufacturing the same as distinguished from the 5 usual intermittent or batch process.

Amongst the advantages derived from my new process are first, the uniformity of the product due to the accurate control of compositions, temperatures, and treatments; second, the improvement in the quality of the varnish because of the elimination of deleterious oxidation of oils and resins, and also because the raw materials are subjected to individual treatments uninfluenced by the 10 other ingredients; and third, the reduction of cost through the elimination of unnecessary handling of materials and apparatus, through increase of output per unit equipment, through elimination of repair charges 15 incident to the operation of kettles and trucks in contact with the intense heat of the cooking fires of the batch process, and the saving of fuel by avoiding the intermittent heating and cooling of the apparatus.

In order to more fully understand the new process it may be stated that varnish is essentially a solution of a resin in an oxidizable oil or volatile solvent or both, the subsequent volatilization of the solvent and oxidation 20 of the oil resulting in a thin film of protective material on the surface to which the varnish has been applied. The resin may be a natural product or a synthetic product depending upon the type of varnish to be produced and is sometimes given a preliminary heat treatment to increase its solubility. The oil is generally, although not necessarily, 25 "bodied" either before or after the solution of the resin, this bodying being accomplished by heating to a predetermined temperature. The bodying is generally considered as a polymerization accompanied by a partial oxidation, although the oxidation is believed to be disadvantageous.

In the present state of the art the varnish is manufactured by an intermittent process, the batches varying in size from fifty (50) to twelve hundred (1200) or more gallons in size, according to the nature of the product 45 and the type of the kettle used. The smaller size batches are ordinarily made in portable kettles, while the larger ones require a stationary or "set kettle" installation in which

the batch may be reduced as well as cooked before leaving the kettle. Assuming that the raw materials are of a standard quality the uniformity and quality of the resultant varnish made in either installation depends upon the accuracy of proportioning the raw materials entering into the batch and the control of the heat treatment of the oils and gums. These two important factors are influenced by the "personal equation" of the operator in charge of each kettle.

In the new process the raw materials pass in a continuous stream through a series of kettles or other containers in which the various stages of heat treatment are carried out. Each step requiring an individual treatment has assigned to it a special kettle 60 into which the material is fed at a predetermined rate and from which the semi-finished product is discharged in such quantity as is required by the particular formula 65 under manufacture at the time. In this way 70 each raw material may be treated free from the deleterious influence of any other material or from undue oxidation, the latter being accomplished by the sealing of the heating chamber. Furthermore, the heating chambers may, if desired, be operated under 75 vacuum to accelerate reaction or may be subjected to air blast to promote oxidation in certain cases. The compositions of the varnishes made by this process are controlled by 80 synchronizing the discharge of the several feeders handling the raw or semi-finished ingredients. It is preferable also to control 85 the heat treatment through variation in quantity of flow and since temperature is an 90 important factor in the heat treatment the process lends itself readily to automatic control by providing a thermostat to regulate the rate of flow.

In the drawings:—

Figure 1 illustrates diagrammatically the apparatus used for carrying on the process;

Figure 2 is a diagram illustrating the automatic control of the oil feeding and resin 100 feeding devices;

Figures 3 and 4 show the contact arms of the thermostatically controlled switch in the two positions.

As an example of the operation of the new 105 process, the following description is given of

the steps for producing a black baking japan made from the following ingredients:—

Asphaltum gum	200 lbs.
Perilla oil	20 gals.
Linseed oil	20 gals.
Turpentine	100 gals.
Metallic drier	2 lbs.

The two oils are mixed in proper proportions in each of the supply containers A and A' controlled by the valves B and B' and preferably provided with steam heating coils B² for maintaining the oil at a substantially constant temperature. A centrifugal pump C is arranged to withdraw the oil from said tanks and deliver an excess quantity to a standpipe D equipped with a pressure or head controlling device D' having an overflow pipe D² for returning the excess oil to the inlet side of the pump C. As shown in Figure 1 the height of the liquid in the standpipe D is controlled by raising or lowering the container D' by means of the movable support E slideable upon a bearing E' and actuated by the screw E² rotated in the threaded member E³ by the reversible motor N. A flexible pipe F connects the container D' with the standpipe D, preferably at a point not immediately adjacent the inlet to said standpipe nor to the outlet F². From the standpipe the oil flows through calibrated orifice H and meter H'. For practical purposes, the orifice may be made adjustable by making it an integral part of an adjustable stopcock, which is in the case in question adjusted to the predetermined capacity by means of the meter.

G is a tank containing oil or some other suitable heating material for maintaining a uniform temperature in the coil pipe G' connected to the meter H'. A burner G³ or other suitable means is provided for heating the medium to the proper temperature and a mechanical agitator G⁴ is placed within the coil G' to continuously circulate the heating medium around the coils. This agitator is preferably provided with the blades G⁵ so arranged as to circulate the heating medium downward through the coil G' and is driven by any suitable mechanical means (not shown). The purpose of this apparatus is to pre-heat the oil to a temperature sufficiently high to enable the second kettle to operate at a uniform temperature throughout. The temperature of the first kettle is usually, although not necessarily, maintained below the point where any appreciable reaction takes place within the oil, for example, a temperature of 525-550° F. From the coil G' the mixed oils pass into a reaction tank I provided with a series of cylindrical baffles I' so arranged as to cause an up and down circulation. The oil is preferably introduced centrally of the apparatus, passing through the apertures I² as shown by the arrows, finally

reaching the outer cylindrical space from which an overflow pipe I⁴ leads to the succeeding unit J. A suitable burner I⁵ is arranged to heat the tank I to a temperature sufficient to carry on the chemical reactions 70 for bodying the oils.

The tank J contains a mechanical agitator J', preferably arranged to cause an upward current therethrough, and the tank is also provided with a baffle J², preferably in the 75 form of a tube extending downwardly nearly to the bottom of the tank. The outlet of the tank J is near the top of the baffle tube J², thereby protecting the finished mixture from undue agitation. Arranged above the tank 80 J is a feeding apparatus K for discharging the proper amount of resin or asphaltum gum to be incorporated into the varnish. The feeder is arranged to be continuously operated so as to discharge the gum at a rate proportional to the flow of oil through the apparatus. For this purpose, a suitable regulating device is provided and as diagrammatically shown, comprises a rotatable member K' having recesses K³ therein, this member being housed in a cylindrical housing K⁴ connected to a hopper K⁵. A discharge conduit K⁶ leads to the tank J and the member is rotated by a motor K² through suitable gearing K⁷. The gum is melted upon reaching the 90 solution by the mechanical agitator, heat being also supplied to the tank through a suitable burner J³. The overflow from the unit J passes into an accumulator tank L, which serves merely to collect the mixed product 100 and to periodically discharge the same into the thinning vats (not shown) by the operation of the manually controlled valve L'. The conduit L² through which the material enters the accumulating tank preferably extends to the bottom of the tank L in order to maintain a liquid seal at all times to avoid flashing. A burner L³ is also provided under the tank L to maintain the mixture sufficiently fluid for transferring.

With the apparatus as thus far described, the flow of oil is regulated by the height of the liquid in the head controlling device D' acting through the calibrated orifice H, and by maintaining a uniform temperature of the oil passing through the orifice a very accurate control may be obtained. In order to accurately control the temperature and the time of reaction it is only necessary to vary the hydrostatic head 110 upon the apparatus, thereby increasing or decreasing the flow. This preferably is done automatically by providing a suitable thermostatic regulator M near the outlet of the tank I which is adapted to operate through suitable electrical connections to control the operation of the motor N and the speed of the motor K².

An arrangement is provided for accomplishing this purpose and is diagrammati- 130

cally shown in Figure 2, where the operation of the thermostat M controls a reversing switch M' electrically connected to the motor N so as to energize the same either in the forward or the reverse direction according to the position of the switch M' . This switch also is electrically connected to a reversible motor O adapted to control the field resistance Q of the motor K^2 so as to increase or decrease the speed of said motor. Thus, as shown, the motor O is electrically connected to a rotatable screw R threadedly engaging the movable contact P . This contact is therefore, moved in one direction or the other, according to the rotation of the motor O and consequently increases or decreases the field Q , thereby correspondingly changing the speed of the motor K^2 driving the rotatable regulator K' . S represents a manually operable switch for controlling the operation of the motors N and O , in case it is desired to eliminate the thermostatic control. Electrical apparatus of the character diagrammatically illustrated in Figure 2 is commercially obtainable and what I wish to illustrate is merely an apparatus for simultaneously regulating the effective head upon the orifice and the feed for the resin or asphaltum gum. With the arrangement as described, both of these variables are controlled by the temperature of the liquid in the tank T and both are maintained operating at proportionate rates.

A more specific description of the electric circuits represented in Figure 2 is as follows:—

The switch M' comprises four contact points 10, 11, 12 and 13 and the contact arms 14 and 15, the latter being pivoted respectively at 16 and 17 and being connected to the thermostat M by arms 18 and 19. The arrangement is such that upon movement of the thermostat in one direction arms 14 and 15 contact with the points 10 and 13 respectively, as shown in Figure 3, while in the other direction the arms contact with the points 11 and 12 respectively as shown in Figure 4. The contacts 10 and 12 are connected together and contacts 11 and 13 also are connected together. The armature 20 of the motor O , has its terminals 21 and 22, respectively connected to points 10 and 11, while the armature 23 of the motor N has its terminals 24 and 25 connected respectively to points 10 and 11. The fields 26 and 27 of the respective motors O and N are connected in multiple between the positive terminal and the contact arm 15, while the negative terminal is connected directly with the contact arm 14. The motor K^2 is arranged in a circuit 28 including the field resistance Q and the manually controlled switch 29. The switch S is similar to the switch M' except that it is manually controlled, and the various elements of the switch S are connected to the corresponding elements of the switch M' so

that either device may be used for controlling the various motors.

In the operation of the control system it will be observed that by closing the switch 29 the motor K^2 will be driven at a predetermined speed depending upon the amount of the resistance Q in the motor circuit 28. When the reversing switch M' is in the position shown in Figure 3, current from the positive terminal will pass through the fields 26 and 27 which are in parallel, the contact arm 15, contact point 13, then dividing and passing through armatures 20 and 23 respectively and finally returning to the contact 10 where the circuit is completed to the negative terminal through the switch arm 14. Thus the motors O and N will be energized and revolve in certain predetermined directions, the former adjusting the field resistance Q and the latter adjusting the height of the bracket E . When the thermostat is moved in the opposite direction to the position shown in Figure 4, it will be obvious that the switch arm 15 now contacts with the point 12, while the switch arm 14 contacts with point 11. In this position of adjustment, the flow of current through the fields 26 and 27 takes place in the same manner as in the preceding adjustment, but when the switch arm 15 is reached, it will be obvious that the flow through the armatures 20 and 23 will be in the reverse direction from the preceding arrangement. Therefore, the motors O and N by having the polarities on the armatures changed will rotate in the reverse direction. When the switch M' is in the position shown in Figure 2 with the contact arms 14 and 15 in neutral position, no current will flow through either of the motors O and N and the latter will remain stationary. In this stationary position the motor K^2 still operates at a predetermined speed depending upon the adjustment of the field resistance Q and the arm E remains at a predetermined height so as to maintain a predetermined head upon the calibrated orifice H' .

In the making of various types of varnish, it is often desirable to introduce a siccative which is usually introduced by directly adding a proper material to the mixture but this new process lends itself readily to supply the necessary siccative from the surfaces of the kettles or baffles or other metallic surfaces by choosing suitable materials and providing the necessary amount of surface. The kettle may be and preferably is made from metal not attacked by oils or gums if sufficient surface is otherwise provided. In the particular process described it has been found that any iron surface will supply the necessary siccative for the process.

The material collected in the accumulating unit L must ordinarily be mixed with a thinner for producing a commercial varnish, but

this apparatus forms no part of my invention and the usual method may be employed of mixing the product obtained in the above described process with a volatile thinner in 5 large stationary tanks.

While I have specifically described the process as applicable to the manufacture of a baking japan, it will be understood that this process is also applicable to making a large 10 number of other types of varnish, and in modifying this apparatus for these other specific types, it is only necessary to provide units for carrying on the heat treatments and the mixing of the raw materials entering 15 thereinto. Each of the heat treatment kettles is heated to a predetermined temperature, ranging usually from 400 to 650° F., and the rate of flow of the liquids may be controlled by the hydrostatic head acting through a calibrated orifice while maintaining a substantially 20 constant temperature in the liquid.

I wish it also understood that the various units of the apparatus may be placed under suitable ventilating hoods to withdraw the 25 fumes, or that they may be provided with covers and operate either under vacuum to accelerate the reactions or under an air blast to promote oxidation if desired.

It will also be obvious that instead of employing the motors N and O for regulating the hydrostatic head and the feeding of the resin, suitable manually operable means may be employed if desired. This apparatus, however, would require more attention upon 30 the part of the operator than the thermostatically controlled apparatus which is the preferred form.

While I have illustrated the pre-heated tank G as being composed of a coil G' surrounded by an oil bath, in the making of certain types of varnish, it is not necessary to employ a coil, but the oil may be caused to flow directly into the tank G and the temperature will be maintained sufficiently constant because of the agitator G⁵.

In the appended claims the term resin is used to define either a natural or a synthetic product, and includes within its scope asphaltum gum and any other products that are dissolved in oils or volatile solvents for the purpose of obtaining varnish. Likewise the terms liquid varnish-making ingredient and varnish-making oil are intended to cover either an oxidizable oil or a volatile solvent or both.

What I claim as my invention is:—

1. The process of making varnish consisting in passing a liquid varnish-making ingredient in a continuous stream through a series of containers, subjecting said liquid to predetermined pressures and temperatures during the passage, introducing a resin ingredient into said stream at a rate substantially proportionate to the rate of flow of said liquid 65 ingredient synchronously varying the flow of

said liquid ingredient and said resin ingredient to maintain uniformity in the proportion of ingredients and the heat treatment thereof.

2. The process of making varnish consisting in passing a varnish-making oil in a continuous stream through a series of containers, subjecting the oil to heat treatment during the passage, continuously introducing a resin thereinto at a rate substantially proportionate to the flow of said oil, automatically varying the flow of oil to maintain a uniform temperature during heat treatment, and automatically varying the amount of resin introduced to maintain a uniform proportion of 70 ingredients.

3. The process of making a varnish consisting in passing a varnish-making oil through an apparatus in a continuous stream, subjecting the stream to heat treatment, continuously introducing resin into said stream at a predetermined point in its passage, varying the rate of oil flow to control the reactions in 85 said apparatus and maintaining a substantially constant proportion of ingredients.

4. The process of making a varnish consisting in continuously passing a varnish-making oil through a series of containers, introducing resin into one of said containers at a proportional rate to the oil, subjecting the 90 ingredients to predetermined conditions of temperature pressure and agitation in the respective containers to effect the reactions, and controlling the reactions in said containers by varying the rates of flow of the oil and the resin while maintaining the same in substantially proportionate relation to each other.

5. An apparatus for producing varnish comprising a series of containers connected 105 by conduits, each of said containers being provided with means for subjecting the contents thereof to a predetermined condition of temperature pressure and agitation, means for effecting a flow of a varnish-making oil through said apparatus, means for automatically varying the flow of oil to maintain a substantially constant temperature and means for introducing resin therein at a rate 110 substantially proportionate to the rate of flow of said oil.

6. The process of making varnish which consists in subjecting a varnish-making oil to a variable hydrostatic head passing the oil through a calibrated orifice into a mixing apparatus while maintaining a substantially constant heat-supply, subjecting said oil to a heat treatment in said apparatus, introducing resin into said oil and varying the hydrostatic head effective upon said calibrating orifice to control the rate of flow through said apparatus to the amount required to maintain a constant temperature in the mixing apparatus.

7. The process of making varnish which 130

consists in continuously feeding the ingredients of the varnish into a mixing apparatus, subjecting the materials to heat treatments during the passage thereof through the apparatus, and controlling the temperature of the reaction by increasing or decreasing the feed of the respective ingredients into the apparatus.

8. The process of making varnish which 10 consists in passing a liquid varnish-making ingredient in a continuous stream through a series of containers, subjecting said liquid to predetermined pressures and temperatures during the passage, introducing a second ingredient into said stream at a rate proportionate to the rate of flow of said liquid ingredient and controlling the reaction by in-

creasing or decreasing the rate of flow of the ingredients through the apparatus.

9. An apparatus for manufacturing varnish comprising a varnish-making oil reservoir, means for maintaining oil under predetermined hydrostatic pressure, a pre-heating unit connected to said oil reservoir, a heat treating unit connected to said pre-heating unit, baffles in said heat treating unit forming passages therein, a mixing apparatus connected to said heat treating unit, means for feeding solid material into said mixing apparatus, and means for regulating the hydrostatic pressure upon said apparatus to control the flow of oil thereto

In testimony whereof I affix my signature.
